UNITED STATES PATENT OFFICE.

FRED E. LEE, OF DOWAGIAC, MICHIGAN.

DESIGN FOR A COOKING-STOVE.

SPECIFICATION forming part of Design No. 26,656, dated February 16, 1897.

Application filed March 9, 1896. Serial No. 582,489. Term of patent 14 years.

To all whom it may concern:

Be it known that I, FRED E. LEE, a citizen of the United States, residing at the city of Dowagiac, in the county of Cass and State of Michigan, have invented a certain new and useful Design for a Cooking Stove or Range, of which the following is a specification.

My invention relates to a design for a cooking stove or range.

10 My invention relates more particularly to the stove or range illustrated in the accompanying drawing, which presents a perspective view of the stove or range constructed in accordance with my design.

15 The leading feature of my design is more particularly the peculiar configuration and ornamentation of the various portions of the stove.

20 The outline features of the design are not essentially new.

The stove shown is supported upon a base B, provided with legs, the whole of which is ornamented, as shown in the accompanying drawing, each leg being so formed as to pre-

25 sent a finished name-plate for the name of the stove. Supported upon this is the main body of the stove A, the various parts of which are ornamented, as indicated in the drawing. The reservoir C is detachably supported to

30 the back of the stove and is ornamented as illustrated. A plate C' is hinged to the side

of the reservoir exposed to view for the purpose of opening and closing a plate bearing the directions for operating the range, and is designed as indicated in the drawing. To 35 the side of the stove which ordinarily comes next to the wall is a bracket D, which supports little swinging shelves and which is also a cresting to finish the upper part of the stove. These parts enumerated form a complete cooking 40 stove or range which is very ornamental in its appearance.

Having thus described my invention, what I claim as new, and desire to secure by Letters Patent, is—

45 1. The design for a cooking stove or range substantially as described and shown.
2. In a design for a cooking stove or range the reservoir C with the hinged plate C' in connection therewith substantially as de- 50 scribed and shown.

3. In a design for a cooking stove or range, the ornamental bracket or cresting D at the top of the same, substantially as described and shown.

55 In witness whereof I have hereunto set my hand and seal in the presence of two witnesses.

FRED E. LEE. [L. S.]
